(57) **CLAIM**

The ornamental design for a fastener tool, as shown and described.

DESCRIPTION

FIG. 1 is a perspective view from the left side of an embodiment of a fastener tool showing a new design.

FIG. 2 is a bottom plan view of the embodiment.

FIG. 3 is a top plan view of the embodiment.

FIG. 4 is a front elevational view of the embodiment.

FIG. 5 is a rear elevational view of the embodiment it being understood that the broken line illustration within the figure forms no part of the claimed design for which a patent is sought.

FIG. 6 is a left side elevational view of the embodiment; and, FIG. 7 is a right side elevational view of the embodiment.
